UNITED STATES PATENT OFFICE.

GEORGE JOHN WHELAN, OF MINNEAPOLIS, MINNESOTA.

EGG-WASHING MACHINE.

No. 892,104.

Specification of Letters Patent.

Patented June 30, 1908.

Application filed June 27, 1907. Serial No. 381,070.

To all whom it may concern:

Be it known that I, GEORGE JOHN WHELAN, a citizen of the United States, residing at Minneapolis, in the county of Hennepin and State of Minnesota, have invented certain new and useful Improvements in Egg-Washing Machines; and I do hereby declare the following to be a full, clear, and exact description of the invention, such as will enable others skilled in the art to which it appertains to make and use the same.

My invention has for its object to provide a machine by means of which eggs may be washed in large quantities, and to this end it 15 consists of the novel devices and combinations of devices hereinafter described and defined in the claims.

The improved washing machine is illustrated in the accompanying drawings, wherein 20 like characters indicate like parts throughout the several views.

Referring to the drawings, Figure 1 is a plan view of the improved machine. Fig. 2 is a side elevation of the machine, some parts 25 being broken away and some parts sectioned. Fig. 3 is a transverse section taken on the line $x^3 x^3$ of Fig. 2. Fig. 4 is a detail in section taken through one of the screens or perforate decks on the line $x^4 x^4$ of Fig. 1; and Fig. 5 is a 30 detail in section taken through one of the screens or perforate decks on the line $x^5 x^5$ of Fig. 1.

All parts of the machine are mounted on a frame-work 1 of suitable construction, from 35 the upper portion of which a vibratory shoe or bottomless box 2 is supported, as shown, by means of yielding metal straps 3 secured at their upper ends to the upper portion of said frame, and at their lower ends to the 40 lower front and rear portions of the said shoe 2. At its sides, the shoe 2 is connected by a transverse crank shaft 8 mounted in suitable bearings in the frame 1. The crank disk 6 is 45 in the form of a spur pinion that meshes with a spur gear 9 mounted on one side of the frame-work 1 and provided with an operating crank 10, by means of which it may be rotated to impart a vibratory movement to the 50 shoe 2. As shown, supporting bars 11 extend transversely of the shoe 2 and are secured to the bottom portion thereof. These supporting bars 11 support a stack of separable rectangular sieve frames 12, each of which is provided with a screen or perforate

deck 13. These screens 13 constitute bottoms to the sieve frames 12, and at their front and rear portions they are curved upward, as best shown in Figs. 2 and 5, and are secured to the upper edge portions of the said frames. At 60 their side edges, the screens 13 underlie cleats 14 secured to the sides of the said frames 12, as best shown in Figs. 1 and 4. Secured to the frame 1, below the shoe 2 is a hopper 15 having an inclined bottom that terminates in a 65 discharge spout 16. Overlying the shoe 2 and the bank of screens is a perforated spraying pipe 17 which, as shown, is supported at its ends by vertical projections 18 on the frame 1. This spraying pipe 17 is preferably 70 triangular in cross section, as best shown in Fig. 3, and water is supplied thereto from a pipe 19 that leads from any suitable source of supply.

The eggs to be washed are placed on the 75 screens 13, as shown in Figs. 1 and 2, and water is sprayed over the upper layer of eggs from the spraying pipe 17, while the shoe 2 is given vibratory motion by rotation of the crank-equipped gear 9. The water will, of 80 course, percolate through the several screens and come into contact with all of the eggs. Under vibratory movements of the shoe and the screens, the eggs will be rolled back and forth and will continually change their relative positions with a slow and irregular rotary action, so that they are caused to grind 85 against each other and against the screens, while at all times subject to the spray of water, and under this action they will be thoroughly cleaned. In fact, they will be not 90 only thoroughly cleaned, but actually polished. The water dripping from the eggs will be caught by the hopper 15 and directed by the spout 16 into any suitable receptacle 95 (not shown). The rolling or shifting movements of the eggs under the vibratory movement of the shoe and screens is due to the inclined upper and rear extremities of the screens which permit slight traveling movements of the layers of eggs on the screen and at the same time hold the eggs closely pressed together.

It will, of course, be understood that any 105 desired number of the egg supporting screens or perforate decks may be employed, and it will also be understood that vibratory movements may be imparted to the screen supporting shoe, and that water may be supplied to the eggs by any suitable means. 110

The egg washer above described has been put into actual use and the efficiency thereof has been demonstrated. It will, of course, be understood that this washing apparatus is capable of use for washing fruit and various other round, oblong or approximately round bodies.

What I claim is:

1. In a washing machine of the kind described, a screen mounted for vibratory movements and provided with end or marginal portions that are gradually upturned, the main body portion of said screen being approximately smooth, flat and free from obstructions, and the said screen being exposed.
- 10
- 15

2. In a washing machine of the kind described, a screen mounted for vibratory movements and provided with end or marginal portions that are gradually upturned, 20 the body of said screen being approximately smooth, flat and free from obstructions, in combination with a spraying device located above said screen, and the said screen being exposed.

25

In testimony whereof I affix my signature in presence of two witnesses.

GEORGE JOHN WHELAN.

Witnesses:

H. D. KILGORE,
MALIE HOEL.
